COMBINED ASHTRAY AND COASTER

Harry W. Kent, 2306 Scottwood,
Garland, Tex. 75040

Filed Aug. 7, 1968, Ser. No. 13,049

Term of patent 14 years

Int. Cl. D27—03

U.S. Cl. D85—2

FIG. 1

FIG. 3

FIG. 1 is a front perspective view of a combined ashtray and coaster, showing my new design;

FIG. 2 is a top plan view; and

FIG. 3 is a side elevational view thereof.

I claim:

The ornamental design for a combined ashtray and coaster, as shown.
